JOSEPH W. SCHLOSS, OF NEW YORK, N. Y.

DESIGN FOR BRAID.

SPECIFICATION forming part of Design No. 22,424, dated May 9, 1893.

Application filed February 7, 1893. Serial No. 461,395. Term of patent 3½ years.

To all whom it may concern:

Be it known that I, JOSEPH W. SCHLOSS, a citizen of the United States, residing at New York, in the county of New York and State of New York, have invented a certain new and original Design for Braids, of which the following is a full, clear, and exact description.

My new and original design relates to braids for dress trimming, and is illustrated in the two figures of the accompanying drawings.

The design has the general appearance of a flat band or strip of braid a, having substantially straight, parallel edges a', upon the face of which is a zig-zag or serpentine band or strip b. The two bands are made in contrasting colors, so as to emphasize the appearance of one band lying upon the face of the other. This appearance is furthermore emphasized by making the band b, in relief, as clearly indicated in Figure 2 which represents a cross section of the braid. The band b is of less width than the band a, and its deviations from a straight line alternating from one side to the other of band a, are just sufficient to 25 make its edges coincide with the edges of band a.

I am aware of the existence of a braid in which there is a central serpentine band, the deviations or curves of which on each side are capped by short, curved, border lines of a contrasting color, between each curve of which there is a clearly defined space, and such I do not claim. It will be observed that my design has substantially straight edges and that the 35 only curves in the figures are in the central serpentine band.

Having thus described my invention, I claim—

The design for braid herein described and 40 illustrated in the accompanying drawings.

In testimony whereof I subscribe my signature in presence of two witnesses.

JOSEPH W. SCHLOSS.
